ANTIPANIC THEATER AND THE LIKE

August B. Christensen, Hellertown, Pa.

Application November 23, 1937, Serial No. 176,115

2 Claims. (Cl. 20—1.12)

The invention relates to the design and construction of theaters, auditoriums, and other places of public assemblage, and has for an object to provide for the safety of audiences in emergencies which require an audience to vacate the building quickly, as, in case of fire, explosion, earthquake, and other serious occurrences which would threaten the safety of an audience remaining in the building.

10 An important aim of the invention is to obviate the need for the persons in an audience to make their own ways from the building in such emergencies, and particularly to avoid the requirement for the audience to reach the doors 15 and other usual exists in order to leave the building, so that the possibility of jamming of a crowd at such exits is avoided, as well as similar disks on stairways within or without the building.

It is an object of the invention to prevent an audience from inflicting injury upon its members 20 in the hysterical panic which accompanies fear as has often occurred in the past among crowds of usually normal individuals.

To these ends it is an aim of the invention to 25 present means whereby an audience may be moved translationally while seated in its chairs, and as a unit, from the building to a place of safety, all being evacuated simultaneously.

Additional objects, advantages and features of 30 invention reside in the construction, arrangement and combination of parts involved in the embodiment of the invention as will appear from the following description and accompanying drawing, wherein—

35 Figure 1 is a vertical section of a construction of building and apparatus embodying my invention, the section being parallel to one row of seats, the structure being shown in condition for normal use.

40 Figure 2 is a vertical section at right angles to Figure 1 from the direction of the stage, screen or proscenium.

Figure 3 is a fragmentary elevation from the right of Figure 1.

45 There is illustrated a portion of a building structure 10, which may be of any conventional architectural detail as to parts not shown, in which a platform or stage 11 of any usual construction may be provided, the details of this 50 being formally indicated without detail since they form no essential part of the present invention. The floor 12 of the auditorium is a movable deck structure stepped or not, conforming to approved construction practices for such a structure as 55 hereinafter indicated. It is lower toward the

stage than it is at the back part which is at the right in Figure 2. The main fixed building structure may include a bed floor 13 set a considerable distance below the deck 12 and having mounted thereover a series of parallel rails 14 inclined laterally and downwardly to the right and carried on pillars 15 or otherwise. The building also includes a permanent fixed wall portion 16 at the side of the auditorium, having an opening 17 therein the top of which is at a height of a standing person, for purposes to be indicated. The rails 14 are continued through this opening with uniform inclinations, downwardly onto a lower area 18 without the building. The rails 14 over the area 18 may also be supported on pillars 16, 15 if required. If this area is within an excavation, the sides of the latter should be suitably walled, and proper drainage and access and egress provided, these details not being illustrated, since they are well understood details of architecture. 20 In the event that the building is built in a situation where the grade corresponds to the slope required or may be made so, and at the right level, the pillars 15 may be omitted as expedient, and the rails laid upon a properly adjusted grade 25 with any approved footings suitable for the purpose.

Movable upon the rails and carrying the deck 30 there is a carriage 20 consisting of a frame supporting the deck 12, and having wheels 19 at 35 suitable intervals on each of the rails 14.

It should be noted that this carriage frame work is constructed in units each identical with the other, except in height, and that these units are assembled and secured together to form the 35 complete supporting structure for the deck 12, so that each respective section of deck is supported independently of the remainder, and the liability of a general collapse by failure of the frame work 40 at one point only is minimized. The wheels 19 are arranged at front and rear sides of the frame sections, so that at mutually adjacent sides of respective sections two sets of wheels are 45 close to each other. While these might be arranged to run on a single rail, in the present instance they are on spaced closely parallel tracks, and consequently, the rails 14 are arranged in pairs closely spaced, each pair receiving thereon wheels of respective frame sections. 50

Seats 21 of standard structure are set upon the deck, and if desired, these may be arranged in groups 22 positioned within the vertical boundaries of respective frame sections, so that transverse aisles 23 are formed in the auditorium, 55

located over the two rails of mutually adjacent pairs.

The carriage sections are preferably secured together so as to form a unitary structure movable 5 without relative displacement of any of the parts of the carriage structure or of the deck areas.

The carriage work is extended as at 24, at its lower part under the wall 16 and beyond the vertical boundary of the chairs and a side aisle 10 between the chairs and wall 16 or its continuation, and on this lower extension part an entrance platform 25 is constructed, having a parapet 26 at its outer edge parallel to the plane of the wall 16 and spaced outwardly of that plane to afford 15 standing room for a proper number of people outside of that plane when the deck is in normal position. This extension 24 carries a false wall section 27, which when the deck 12 is in normal position alines with the wall 16 and fits within 20 the opening 17 in the wall 16, closing the same. In the false wall 27 there are incorporated wall frame sections 28 alined with respective carriage sections, and in each of the wall sections 28 respective sets of doors 29 are provided appropriate 25 to the uses contemplated, and adapted to use as entrances to the building when the carriage structure is in normal position, or they may be used exclusively for access to and from the carriage element and its deck when in emergency 30 position.

The carriage structure and its deck and deck load, as well as the false wall structure 27, and platform 25, are held in normal position as a stationary part of the building in which they are 35 incorporated, by means of a series of cables 30, attached to the inner lateral edge of the deck and carriage structure, where it is very close to the rails 14 since the latter are spaced just enough below the deck at this side of the carriage and 40 deck structure to accommodate the minimum truck or skid structure.

The cables are wound on drums 31 fixed on a common shaft 32 mounted below the rails and operated conventionally from a motor 33 located 45 on the floor 13, the shaft 32 being journalled in suitable journal brackets 34 mounted on the same floor. The shaft is located below all parts of the deck, and the cables are carried upward from the drums over respective idler pulleys 35 so as to bring the cable ends properly into a plane with the deck part to which they are connected parallel to the rails 14.

The shaft 32 is also provided with a brake drum and brake device 36 controlled in any preferred 50 manner, a brake wheel 37 being shown.

There is indicated an unloading platform 38 without the building beside the emergency position of the carriage and deck structure, so that when the latter is in emergency position the 55 audience may leave their seats and file down the aisles leading to the front of the deck and step onto the platform 38. Any desired auxiliary ap-

paratus for releasing the carriage from initial position, and for stopping it at the lower ends of the inclined tracks may be employed, as discretion dictates. The release device may comprise a part of the brake unit 36. Other means for braking or controlling movement of the carriage from normal position to emergency position may be employed without departing from the spirit of the invention as hereinafter claimed, as well as various other modifications made 10 within the scope of the said claims, and I do not regard the invention as limited to the specific construction herein illustrated.

I claim:

1. A structure of the character described comprising a building structure having a space therewithin to accommodate a floor deck and including a wall having an opening therethrough extending above and below the deck, a pit exteriorly of the building, an inclined trackway mounted within the building below the deck space inclined downwardly from the side of said space opposite the said opening and extending through the opening into the pit, said pit being of a width equal at least to the width of the deck space, a carriage on the trackway, said carriage including support means decreasing in height progressively in the direction of the pit, a floor deck carried by the support means at a level to register with the upper edge of the pit when the carriage is moved therewith, means to control movement of the carriage on the trackway, and means to move the carriage from without the building on said trackway to normal operative position.

2. A structure of the character described comprising a building structure having a space therewithin to accommodate a floor deck, and including a wall beside said space having an opening therethrough beside the space for the deck, and extending therebelow and thereabove; an inclined trackway mounted within the building below the deck space inclined downwardly from the side of said space opposite the said opening extending through said opening without the building a distance equal at least to the width of said deck space, a carriage on said trackway, a floor deck carried thereby, means to anchor the carriage and deck in normal operative position,

means to control movement of the carriage and deck on said trackway, means to control movement of the carriage from without the building on said trackway to normal operative position, means to secure the carriage releasably in initial position, a platform on the lower part of the carriage projected beyond and without the plane of said wall when the carriage is in normal position, and a wall section on said carriage constructed and arranged to close said opening when the carriage is in normal position, and doors in said wall section to form communication with the interior of the building from said platform.

AUGUST B. CHRISTENSEN.
